UNITED STATES PATENT OFFICE.

AUGUST ZIDOVEC, OF SAN RAFAEL, CALIFORNIA.

CAN OPENER.

Application filed July 3, 1922. Serial No. 572,371.

To all whom it may concern:

Be it known that I, AUGUST ZIDOVEC, a citizen of the United States, residing at San Rafael, in the county of Marin and State of California, have invented new and useful Improvements in Can Openers, of which the following is a specification.

This invention relates to improvements in can openers and resides in the provision of a simple, compact, strong and easily operable can opener which is constructed so that it may be easily and cheaply manufactured.

One of the objects of the invention is to provide in a can opener of the character described which includes crossed pivoted handles operating similarly to pliers and takes into consideration novel means for arranging a spring so as to normally force the handles apart, the said spring means being concealed and combined with the pivoted means for the handles in a novel and effective manner.

The invention further consists in the particular combination, inter-relation and association of certain parts and elements thereof with a purpose of generally improving the construction and operation of can opening devices whereby a clean and smooth cutting action may be easily effected.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Fig. 1 represents a top plan view of a can opener constructed in accordance with my invention, a part thereof being broken away for the sake of clearness of construction.

Fig. 2 is a side elevation of the can opener broken away and sectioned at the pivot point for the purpose of illustrating the concealed spring and pivot arrangement.

Fig. 3 is a bottom plan view of the can opener,

Fig. 4 represents a plan view of a blank of which the guide member and knife support are formed.

Fig. 5 is a view in elevation of said member and knife support as when stamped into shape.

Fig. 6 is a view of said member taken at right-angles to Fig. 5.

Fig. 7 is a top plan view of the detail shown in Figs. 5 and 6.

Figs. 8 and 8^a are views in side elevation and top plan of the can grip members.

Figs. 9 and 9^a are views in side elevation and top plan of the knife.

Fig. 10 is a top plan view of the spring.

Figs. 11, 12 and 13 are detail sectional views of spring housing and pivot arrangements of modified forms.

Fig. 14 is a front elevation of the can grip members as when in use.

Fig. 15 is a fragmentary plan view of the opener as when in use.

Referring to the embodiment of the invention shown in the accompanying drawings, the numerals 1 and 2 designate crossed handles which are preferably made of light sheet material and are shaped so as to provide comfortable grip portions. The handles are pivoted adjacent certain ends as at 3 and one handle carries a knife 4 whereas the other is provided with a jaw 5 adapted to engage a can during the cutting operation.

The handles are normally forced apart by spring means forming a part of the invention, which means is incorporated with the pivot 3. The handle 1 is provided with a circular apertured boss 6 pressed out from its inner side and said boss constitutes a socket member. The handle 2 is provided with a circular tubular projection 7 which extends through the aperture of the boss 6 and is bent outwardly laterally, at its outer end to provide a retaining flange 8. The member 7 thus engaged in the apertured boss 6 provides for a strong and efficient pivot connection between the handles. The shape of the boss 6 and member 7 is such that there is provided an annular chamber 9 between the crossed portions of the two handles. A coiled spring 10 is mounted in this annular chamber 9 and its ends engage in recesses 11 provided in the sides of the chamber 9 in the respective handles 1 and 2. This spring is

so arranged that it will at all times force the handles 1 and 2 apart and is entirely concealed between the cross parts of the handles. By this arrangement the handles are pivotally connected and the spring is housed and concealed in a simple, inexpensive and effective manner.

Pivoted at one end to the handle 2 as at 12, is a flat knife supporting and guide member 13, which is preferably formed of one piece of material and upon its under side is provided with a depending arcuate guide flange 14 adapted to engage the outer side of a can during the cutting operation. The 15 knife is detachably secured to a vertically recessed extension member 15 which projects upwardly from the member 13 and receives the knife in its recess. A head 16 is provided on the upper end of the extension 16 and is engaged by the upper end of the knife. The knife is pointed on its lower end and has its cutting edge located on the inner side or edge thereof. By placing the pointed end on the top of the can 20 near the bead and pushing downwardly on the head 16, the pointed end will puncture the can and the cutting edge on the side of the knife will be disposed in position to cut the can top. Cooperating with the flange 14 25 is a shorter and smaller flange 17 which is carried on the member 13 opposite the flange 14 and arranged to extend over the can top and engage the inner side of the bead of the can.

30 The jaw 5 is provided with means adapted to grip the outer side of the can so that the member 13 with the knife thereon will be moved or pulled forwardly and effect a cutting action when the handles are pressed 35 together. The gripping members 18 are so arranged that the bevelled ends thereof are in staggered relation whereby both bevelled edges will contact with the outer side of the can and grip the latter so as to hold the jaw 40 5 against slipping while the member 13 is pulled towards the jaw 5. This means comprises gripping members 18 fixed to and depending from the under side of the handle 1 and having comparatively sharp 45 bevelled ends 19, which ends are adapted to bind against the can. On one end of the jaw 5 there is provided an upstanding flange 21 adapted to be engaged by a 50 resilient hook member 22 carried on the outer end of the member 13. When this hook member is engaged with the flange as shown in 55 Figs. 1 and 2, the handles 1 and 2 are held close together against the action of the spring. As an additional means for holding the handles closed, the handle 1 is provided with a projection 23 adjacent to the members 19 arranged to engage behind the guide flange 17 when the member 13 is swung into 60 position such that the hook 22 may be caused to snap over the end of the flange 21.

To operate the device, the handles are moved apart substantially into position shown in Fig. 15 and the point of the knife is placed on the top of the can and near the upstanding or beaded edge of the latter. By 65 pressing downwardly on the other member 16 the can top is perforated and the knife is moved into position to cut through the top of the can. The knife is caused to penetrate the top of the can in such manner that the 70 flanges 14 and 17 will lie on opposite sides of the upstanding bead of the can and serve to guide the knife during the cutting operation. The gripping members 19 are then caused to engage the outer side of the can 75 while the jaw portion 5 of the handle extends over the top of the bead. By raising the handles and closing them together, the handle 1 will be moved so as to pull the member 13 with the knife thereon, forwardly and towards the jaw 5, which latter is made stationary due to the grip of the 80 pivot edges 20 of the members 18 with the can. When the handles are moved together they are again expanded and a fresh grip 85 taken with the members 19 at an advanced point against the can. This operation is continued until the top of the can is completely cut. Due to the arrangement of the member 13 when the handles are closed together, the pull on the knife is substantially 90 at right-angles to the adjacent end of the handle to which it is attached and in this way an effective cutting action is provided. The spring housed in the pivot arrangement 95 will force the handles apart of its own accord thus facilitating the operation of the 100 opener.

As shown in Fig. 4, the member 13 may be formed of a single blank of metal, stamped and bent into shape to provide several separate elements, as particularly 105 shown in Figs. 5 and 6.

In Figs. 11, 12 and 13, there are shown modified forms of pivot and spring housing construction. In Fig. 11, the handles 25 and 26 are joined by a common pivot member 27 in the form of a rivet and are provided with outwardly pressed annular grooves 28 which form a housing for the spring, not shown, each of the grooves being provided with an off-set portion 29 to facilitate the anchoring 110 of the ends of the spring.

In Fig. 12, the handles 30 and 31 are joined by a tubular projection 32 formed integral with and struck out from one side of the handle 31. The projection passes through an opening 33 in the handle 30 and is then bent outwardly as at 34 so that it is held in place. In forming the projection 32, the handle 30 is curved so that there is provided an annular portion 35 in which the spring, not shown, may be housed.

In Fig. 13, the handles 36 and 37 are provided with apertured pivot pin bosses 38 130

surrounded by annular depressions 39 which combined form the chamber for the spring. This construction may be provided by stamping each handle in a similar manner.

5 As particularly shown in Fig. 14, the gripping members 19 are inclined or bevelled so that the lower portion of the sharpened edge projects outwardly at a greater distance than the upper portion. This will 10 cause the sharp or bevelled edge to project under the edge or bead of the can and prevent the tendency of the gripping members to slip upwardly.

As shown in Fig. 5, the flange 14 is inwardly off-set or bevelled at its upper portion opposite the bead of the can, as at 40. By having this portion bevelled or inwardly off-set the flange clears the bead of the can. When the gripper members 10 engage the 20 bead of the can, a series of nicks or rough places are provided which if engaged by the flange 14 would interfere with the smooth operation of the cutting. The beveling of the flange 14 thus prevents the 25 engagement of the flange with the nicks on the bead and renders the cutting operation much more reliable and smooth. Another point of advantage is that the knife is provided with a barb or shoulder 41 which will 30 prevent slipping of the knife out of cutting position during the cutting operation. An additional feature is that the flange 21 will abut the adjacent side of the handle 2 when the handles are closed and serve as a stop 35 to prevent movement of the handles into position such as will distort or place a strain upon the parts of the device.

The flange 14 provides a shoulder or bevelled off-set, which shoulder serves to 40 prevent slipping of the flange upwardly off of the can.

I claim:

1. A can opener comprising crossed pivoted handles, a can gripping member on one 45 of said handles, a knife supporting member pivoted on the other handle, a guide flange on the knife supporting member arranged to engage the outer side of a can near the upper end of the can, a knife carried by the 50 supporting member, said flange being arcuate and arranged to avoid engagement with that part of the can subject to engagement by the gripping member and another guide flange on the supporting member arranged 55 to engage the inner side of the upper bead of the can.

2. A can opener comprising crossed handles, one of said handles having an apertured socket, an integral projection on the 60 other handle extending through the socket and bent back to provide a pivotal connection, said last named handle having an annular groove registering with the socket and a spring surrounding the projection and 65 engaged in the socket and groove.

3. A can opener comprising crossed handles, one of said handles having an apertured socket, an integral projection on the other handle extending through the socket and bent back to provide a pivotal connection, said last named handle having an annular groove registering with the socket and a spring surrounding the projection and 70 engaged in the socket and groove, said socket and groove having off-set recesses in which the ends of the spring engage. 75

4. A can opener comprising crossed pivoted handles, a knife supporting member pivoted to one handle, a knife on said member, a can gripping lug depending from the other handle at a point near but spaced inwardly from one end thereof and arranged to engage the outer side of the bead at the upper end of the can, said lug having its 80 gripping edge beveled and inwardly inclined from its lower to its upper edge. 85

5. A can opener comprising handles operatively associated with one another, a can gripping member on one of the handles, a knife supporting member on the other handle, a guide flange on the knife supporting member arranged to engage the outer side of a can near the upper end of the latter and a knife carried by the supporting member, said flange engaging the can beneath 90 the bead and constructed to avoid contact with that part of the can which is subject to engagement by the gripping member. 95

6. A can opener comprising handles pivoted to one another between their ends, a can opening knife support pivoted on one of the handles, a can gripping member on the other of the handles, a knife carried by said support, a projection on the second named handle, a hook on the knife support arranged to engage said projection to hold the handles in closed position and spring means normally forcing said handles apart against the action of which said hook holds the handles. 100

7. A can opener comprising handles pivoted to one another between their ends, a can gripping member on one of the handles, a knife support pivoted on the other handle, a knife carried by said support, a guide flange on said support arranged to extend over the top and engage the inner side of the upstanding bead on a can and a guide flange on the support adapted to engage the outer side of a can adjacent the bead. 115 120

8. A can opener comprising handles pivoted to one another between their ends, a can gripping member on one of the handles, a knife support pivoted on the other handle, a knife carried by said support, a guide flange on said support arranged to extend over the top and engage the inner side of the upstanding bead on a can, a guide flange on the support adapted to engage the outer side of a can adjacent the bead and a pro- 125 130

jection on the first named handle adapted to engage the first named flange when the handles are in closed position.

9. A can opener comprising handles pivoted to one another between their ends, a cutter supported on one of the handles, a can gripping member on the other handle, flanges extending longitudinally on the opposed edges of portions of the handles which

extend from the pivot toward the adjacent ends, which flanges are arranged to abut and limit the movement of the handles in one direction and means on one of the handles adapted to hook over and retain the flange on the other handle when the flanges are in abutting position.

AUGUST ZIDOVEC.
